UNITED STATES PATENT OFFICE.

CHARLES WOOD, OF MOULTON, IOWA.

SWITCH-STAND LOCK.

1,089,176.

Specification of Letters Patent. Patented Mar. 3, 1914.

Application filed January 31, 1912, Serial No. 674,494. Renewed January 20, 1914. Serial No. 813,274.

To all whom it may concern:

Be it known that I, CHARLES WOOD, a citizen of the United States, residing at Moulton, in the county of Appanoose and State 5 of Iowa, have invented a new and useful Improvement in Switch-Stand Locks, of which the following is a specification.

My invention is an improvement in switch stand locks, and has for its object the provision of a simple, inexpensive device of the 10 character specified, capable of being applied to existing stands without radical change, by means of which, the dropping of the operating lever into inoperative position 15 after setting the switch to either position will positively lock the switch, that is will lock the operating lever to the stand.

In the drawings, Figure 1 is a perspective view of the improved lock. Fig. 2 is a trans- 20 verse vertical section, and Fig. 3 is an end view of the lock.

In the present embodiment of the invention the stand is of any usual construction, having the table 1 provided with spaced 25 notches 2 and 3, for receiving the operating lever 4, which is pivoted at its inner end to the arm 5 of the switch rod or shaft 6. The arm 5 is provided with a notch 7 for receiving the inner end of lever 4, and the 30 lever is pivoted to the arm 5 by means of a bolt 8. When the lever is swung into horizontal position, the inner end thereof fits the notch 7, and the lever is by the same movement released from notch 2 or 3, so 35 that the switch rod may be turned.

An angle plate 9—10 has its horizontal portion 9 secured to the upper face of the arm 5, in such manner, that one face of the vertical portion 10 of the plate is in alignment with one wall of the notch 7. The body 11 of a padlock is held by the plate, in position to receive the shackle 12 of the padlock, which is held by lever 4, when the lever is in inoperative position. The body 40 45 11 of the padlock is secured to the portion 10 of the plate 9—10 by means of a link 13, arranged on the opposite side of the body from the portion 10, and connected to the said portion by means of bolts 14 and 15. The link 13 is of greater length than the 50 width of the body, extending beyond the

body at both ends of the link, and the bolt 14 is passed through the inner end of the link and the portion 10 of the plate 9—10 while the bolt 15 is passed through the 55 outer end of the link and the said portion 10. As an additional holding means, a bolt 25 is passed through the portion 10 of the plate 9—10 and the lug 24 of the body. The shackle 12 is secured to the reduced upper 60 or inner end 16 of the lever 4, by means of a link or strap 17. The said link is connected to the end 16 of the lever by means of a bolt 18. The link is engaged in a longitudinal slot or opening 19 in the portion 16, and the bolt 18 is passed transversely of the said slot or opening through the end of the strap or link as shown in Fig. 2. The opposite end of the link 17 is connected to the shackle by means of a bolt 70 20, and the shackle is hinged to the body of the padlock in the usual manner as shown in Figs. 1 and 2. The link 13 on the body is arranged above the keyhole 23, so that 75 the said link will not interfere with the insertion of a key. The body 11 of the padlock is provided with the usual perforated lug 24, for receiving one end of a chain. The said lug is however engaged by a bolt 25, instead of the chain, the bolt engaging 80 also the portion 10 of plate 9—10. The body 11 of the padlock is held in position to receive the bolt 26 of the shackle 12, when the lever 4 is engaged with notch 2 or 3, and as the class of padlocks are spring 85 locks, the mere act of dropping the lever into inoperative position also locks the switch, by engaging bolt 26 of shackle 12 with the body 11.

In operation, when the lock 11—12 is unlocked by the usual key, lever 4 may be lifted into horizontal position to operate the switch. After the switch has been thrown into either position, the dropping of lever 4 into inoperative position also locks the 90 lever in such position. The element of human error is thus eliminated, that is so far as failure to lock the switch is concerned. When the switch has been returned to normal position, the operating lever is released, 95 and drops into one of the notches of the stand. The releasing of the lever locks the 100

lever to prevent it from disengagement with the notch.

It will be noted that the entire padlock is carried by the arm 5, and that the switch 5 is locked in either main line or siding positions. The lever is not only locked from being moved into alignment with arm 5, that is from movement into horizontal position, but is also locked in the notch of the table.

10 I claim:

1. In combination with the switch stand, the operating shaft, and the laterally disposed arm secured to the shaft and provided with a recess for receiving the operating lever when said lever is in alignment with the arm, and the operating lever pivoted to the arm, of means for locking the operating lever to the stand when said lever is swung out of alignment with the arm, 15 said means comprising a padlock composed of a locking body having a perforated lug, and a shackle, means for securing the shackle to the lever, and means for securing the body to the arm in position to receive the 20 bolt on the shackle when the lever is swung out of alignment with the arm, said first named means comprising a link, a bolt passing through the link at each end thereof, the outermost bolt passing through the 25 shackle and connecting the link thereto, and the innermost bolt passing through the inner end of the lever, said lever having a slot for receiving the adjacent end of the link, said last-named means comprising a link, a 30 bolt passing through the link at each end, and a bracket plate secured to the arm and having openings for the last-named bolts, each of the said last-named bolts passing through one of the said openings.

40 2. In combination with the switch stand, the operating shaft, and the laterally disposed arm secured to the shaft and provided with a recess for receiving the operating lever when said lever is in alignment with the arm, and the operating lever pivoted to the arm, of means for locking the operating lever to the arm when said lever is swung out of alignment with the arm, said means comprising a padlock composed of a 45 locking body, and a shackle, means for securing the shackle to the lever, and means for securing the body to the arm in position to receive the bolt on the shackle when the lever is swung out of alignment with the 50 arm, said first named means comprising a link, a bolt passing through each end of the link, said shackle having a perforated lug for receiving the outermost bolt, the inner end of the lever having an opening for engagement by the innermost bolt, said last 55 named means comprising a link, a bolt passing through each end of the link, and a bracket plate secured to the stand and having openings for receiving the bolts.

60 3. In combination with the switch stand,

the operating shaft, and the laterally disposed arm secured to the shaft and provided with a recess for receiving the operating lever when said lever is in alignment with the arm and the operating lever pivoted to the arm, of means for locking the operating lever to the arm when said lever is swung out of alignment with the arm, said means comprising a padlock composed of a locking body, and a shackle, means for securing the shackle to the lever, and means for securing the body to the arm in position to receive the bolt on the shackle when the lever is swung out of alignment with the arm, the said means comprising a link for the body and a link for the shackle, bolts passing through each end of each link, the shackle and the inner end of the lever having each a perforation for receiving one of the bolts, and a plate secured to the stand 75 for engagement by the bolts passing through the ends of the link of the body.

4. In combination with the switch stand, the operating shaft, and the laterally disposed arm secured to the shaft and provided with a recess for receiving the operating lever when said lever is in alignment with the arm, and the operating lever pivoted to the arm, of means for locking the operating lever to the arm when said lever is 80 swung out of alignment with the arm, said means comprising a padlock composed of a locking body, and a shackle, means for securing the shackle to the lever, and means for securing the body to the arm in position to receive the bolt on the shackle when the lever is swung out of alignment with the arm.

5. In combination with the switch stand, the shaft, the operating lever, and the connection between the said lever and the shaft for permitting the lever to swing on an axis transverse to the shaft and for preventing angular movement of the lever with respect to the shaft, of a padlock comprising 105 a body and a shackle, means for securing the shackle to the lever, and means for securing the body to the shaft in such relative position that when the lever is swung out of operative position with respect to the shaft and into inoperative position with the switch closed the shackle will engage the body.

6. In combination with the operating shaft of the switch, the lateral arm secured thereto, the lever pivoted to the arm, and the stand having notches for receiving the lever when in inoperative position out of alignment with the arm, of means carried by the lever and the arm for locking the lever out of alignment with the arm and in either notch of the stand, said means comprising a padlock having a body and a shackle, means for connecting the shackle to the lever, and means for connecting the body to 120 the lever.

the arm in position to engage the shackle when the lever is moved into engagement with a notch of the stand.

7. In combination with the operating shaft of the switch, the lateral arm secured thereto, the lever pivoted to the arm, and the stand having notches for receiving the lever when in inoperative position out of

alinement with the arm, of means carried by the lever and the arm for locking the lever out of alinement with the arm and in either notch of the stand.

CHARLES WOOD.
